UNITED STATES PATENT OFFICE.

ELIHU THOMSON, OF NEW BRITAIN, CONNECTICUT, ASSIGNOR TO THE THOMSON-HOUSTON ELECTRIC COMPANY, OF CONNECTICUT.

DOUBLE-CARBON ARC-LAMP.

SPECIFICATION forming part of Letters Patent No. 295,836, dated March 25, 1884.

Application filed April 2, 1883. (No model.)

To all whom it may concern:

Be it known that I, ELIHU THOMSON, a citizen of the United States, and a resident of New Britain, in the county of Hartford and State of Connecticut, have invented certain new and useful Improvements in Double-Carbon Lamps, of which the following is a specification.

My invention relates to electric-arc lamps in which two sets of carbons are employed, one set burning, while the other is held stationary until released by the action of the first set when its (the latter's) carbon is consumed or nearly consumed.

My invention relates more particularly to the special class of double-carbon lamps patented to me by Letters Patent of the United States No. 272,920, in which a catch or locking device of some suitable construction is employed for normally holding one of the carbons from feeding, and is released by or through some positively-acting mechanism controlled directly or indirectly by the descent of the other.

My present invention consists in the combination, with the releasing or feed-controlling clamp for one of the carbons, of a releasing table or stop for said clamp, made movable and normally held out of the position where the clamp will be released, but set into position for releasing said clamp by the action of the other carbon-carrier when its carbon is nearly consumed. The releasing-stop being held away from its releasing position, the feed clamp or clutch will lock or hold its carrier despite any movements imparted to said clutch by the feed-regulating magnet system; but when said stop is set and held in proper position, the movements imparted to the clutch will cause the release and feed and lift of the carbon in the usual way.

My invention may be carried into practice in various ways, some of which I have herein described and shown. For instance, the releasing-stop may be mounted on a support consisting of a lever, placed by a spring or otherwise so as to hold said stop from releasing the clamp, said lever being, however, arranged in the path of a stud or its equivalent on the other carbon-carrier, so that at the predetermined time said latter carrier will raise the stop into position where it will act in com-

bination with the clutch or clamp in the usual way. The descent of the first carrier might be made to effect indirectly the proper movement of the clutch—as, for instance, by controlling the circuit of an electro-magnet whose armature-lever or equivalent mechanism carries or supports the stop for the releasing and feeding clamp of the other; or any other proper combination or arrangement of devices might be employed whereby the condition or position of the feed-controlling stop or detent for the one carbon-carrier shall be controlled by the descent of the other carbon-carrier.

In the accompanying drawings, Figure 1 is 65 an elevation of a double-carbon electric lamp, showing one arrangement of devices that may be employed for carrying out my invention. Fig. 2 shows the invention applied to another form of clutch. Fig. 3 shows a modified form 70 of device for imparting movement to the releasing-stop of the one carbon-carrier from a stud or button upon the other. Figs. 4 and 5 show electro-magnetic device which may be employed for setting the releasing-stop. Fig. 75 6 shows how an equivalent of a projection or stud upon the carrier may be used for controlling the position of the releasing-stop.

Referring to Fig. 1, H H indicate a suitable frame or case, in which the two upper- 80 carbon carriers or rods, R R², are guided and supported, and D indicates any suitable magnet or system of magnets and coils by which the usual reciprocating movements are imparted to the feed-controlling mechanism of 85 the carbon-carriers, so as to produce a lift of the carbon and the formation of the arc, or to allow a downward movement of the carrier and carbon to compensate for wasting at the arc.

M indicates a core or other equivalent part of the magnet or magnet system, the motion of which core is imparted to the clamps, clutches, or other device through a link, l, which latter in the present instance is connected to a 95 pivoted table or lever, L, carrying at opposite ends the supports K K², by which the feed clamps or clutches are supported or actuated. The clamps or clutches for the carriers R R² are indicated at C C², respectively, and are 100 here shown as the same in construction with the clamp shown in prior patents granted to

me. Each consists of a body or guide, d or d^2 , through which the carrier may move, and on which is pivoted a clamping clutch or toe, h or h^2 , which is provided with an extended 5 arm, 5, and is held against the carrier by the action of a spring, S or S^2 , so as to prevent the carrier from moving downward. If, however, the clamp-body d or d^2 be lowered so as to bring the arm 5 against a suitable stop, the 10 pressure of the clamp on the carrier is relieved, so that the carrier may move downward by gravity.

At f f^2 are indicated stops which serve to limit the downward movements of either end 15 of the table or support L.

At g g are indicated stop projections, which serve to limit the upward movement or play of the clutches, and are formed on a plate, P, supported on the lamp-frame, and made vertically 20 adjustable by any suitable means. These stops might be placed to limit the upward play of the end of lever L instead.

The lower or releasing stop for the clamp or clutch C is indicated at J, and is also formed 25 on plate P, or is placed in any other suitable position. This stop is fixed in position during the operation of the lamp.

The releasing-stop for clutch C^2 is indicated at t as supported by or formed on a lever, T, 30 which is pivoted on any suitable support, and normally is held by a spring or gravity in such a position that the stop t for clamp C^2 exerts but little force on the arm 5 during the upward and downward movement of the 35 clutches and supporting parts that takes place during the feeding of carrier R. The spring S^2 can thus keep the clamping-toe h^2 engaged with the carrier R^2 and prevent the latter from moving downward.

40 B indicates a button or stud on carrier R, which is placed thereon in suitable position to engage with and tilt lever T when the carbon of R is nearly consumed. When the lever is tilted, the releasing-stop t is lifted and held in releasing position. Its movement is thus being set is limited by a suitable stop, V. The carbon-carrier R is then prevented from further downward movement, and its weight 45 serves to keep the releasing-stop t lifted. By 50 making the plate P adjustable I am enabled to adjust all the stops at once. This is not, however, essential.

The general operation is as follows: When no current is on, the parts l , L , &c., which 55 support the clutches, are in their lowermost position. The carbons being inserted in their holders R R^2 , the carbon in R will alone come into contact with the lower or negative carbon, owing to the fact that the arm of clutch C is 60 lifted by stop J, so that the carrier R may drop freely. There being no weight or force upon the end of lever T, (because the button B is at its upper position,) the clutch C^2 will be closed upon the carrier R^2 by the action 65 of the spring S^2 , so that this carrier will be held up with its carbon out of contact with the lower carbon, the carrier having been

raised to this position when the carbon is inserted in its socket or clamp. When the electric current is turned on, the lever L is 70 lifted in the usual way, raising the clutches C C^2 nearly or quite to the upper stops, g g , and forming an arc at A. No arc is formed at A^2 , the latter being at starting out of contact with its lower carbon. This continues until 75 the magnet system lowers the arm 5 upon the stop J by lowering the clamp-body by which it is supported. The feeding continues in the usual way until the button B strikes T, when the releasing-stop t for the other clutch is 80 lifted into releasing position and is held up against the stop V, so that when the magnet system lowers the clutch C^2 said clutch will be opened. The stops f f^2 are provided to insure the requisite movements of each clutch, 85 respectively. The rod R^2 now feeds downward, and its carbon makes contact for the first time, forming the arc at A^2 , while the carbons at A, though possibly feeding slightly at the moment of transfer, are not allowed to come 90 into contact again. The feed of carrier R^2 now progresses in the usual way.

In Fig. 2 I have shown my invention as applied to another form of clutch or clamp, known as a "tilting" clutch or clamp. The 95 releasing-stop t is, however, formed upon the end of a link supported from the end of the lever T, which latter is shown as pivoted on the frame H. The fixed releasing-stop g^2 for clutch C is formed upon or attached to the 100 frame H. The stops g g and f f^2 are a little differently supported, and the former, g g , are here shown as arranged to stop the lever L, instead of being arranged in the path of the clutch-arms 5, Fig. 1. The action of the devices is obviously the same as in the arrangement shown in Fig. 1.

In Fig. 3 the support T, for the movable releasing-stop t, is in the form of a bell-crank lever, the arm t^1 of which is arranged in the 110 path of the button B, so that the latter will act upon the incline of the arm and lift the stop by a wedging or inclined-plane action upon the support for said stop. The action is in other respects the same as already described.

Fig. 4 illustrates one arrangement that may be employed for lifting or throwing the stop t into releasing position through the intervention of an electro-magnet controlled by the descent of the carbon-carrier R. N indicates an electro-magnet, whose armature or armature-lever supports or carries the stop t, said electro-magnet being placed in a normally-open circuit, 7, connected to or derived from the lamp-circuits, or to a suitable source of electric current, in such a way that when the circuit 7 is closed the magnet will be energized and the releasing-stop t for clutch C^2 raised into lifting position. Normally the weight of the armature holds the stop t away. When, however, the carrier R descends to a determinate point, the stud or button B makes contact with a suitably-placed contact-spring, q, thus closing the 120 125 130

circuit 7, which circuit remains closed, owing to the presence of the stop q^2 , which prevents further movement of the carrier R, so that the magnet N continues to hold the releasing-stop 5 t in releasing position.

In Fig. 5 an arrangement of circuits is shown, in which current is normally shunted from magnet N, and said shunt is broken, to energize the magnet, by the action of stud or 10 button B. The shunt-circuit is formed through a stud or screw, w^3 , and a contact-spring, w^4 , whose end is in the path of button B, and which is held normally against w^3 by its own 15 resiliency. When the carrier R feeds so far down as to allow the button to bear on the spring, the latter is removed from contact with the stop w^3 , thus breaking the shunt and energizing the magnet N.

I have described a stud or button, B, on the 20 carrier for producing the desired operation of the support for the movable releasing-stop t ; but I do not by any means limit myself to such special device, since the same operation might be produced by other devices—as, for 25 instance, by narrowing or reducing the size of the carbon-carrier at its upper end, as indicated at B^2 , Fig. 6. In this case the stop t is held out of engaging or releasing position by a lever, T, carrying at one end a friction- 30 wheel, which bears upon the carbon-carrier R, as indicated, so as to prevent a spring, Z, from raising the stop t . When, however, the wheel falls into the narrowed or reduced portion of the rod, the spring Z lifts the stop into 35 releasing position. A stop, W, serves to prevent further downward movement of the carrier R.

My invention is not limited to any particular construction of the parts by which the 40 releasing-stop is supported, nor to any particular means for actuating or moving said support, the essence of the invention consisting in moving said stop into operative position through the intervention of devices controlled in their 45 action or operation by the descent of the other carbon-carrier to a predetermined point. Such devices may be mechanical or electro-magnetic, and may be controlled directly or indirectly and mechanically or magnetically by the movements of the carbon-carrier.

My invention may be readily put into other forms that will obviously suggest themselves to those skilled in the art.

What I claim as my invention is—

55 1. The combination, with two carbon-carriers in an electric-arc lamp, of a movable releasing-stop for the feeding mechanism of one carrier, and suitable means for bringing said stop into releasing position upon the descent of the other carrier to a predetermined position.

2. The combination, in a double-carbon lamp, of a releasing-clutch for one of the carbon-carriers, a movable releasing-stop for said clutch, and means for bringing said stop into 60 releasing position upon the descent of the other carrier to a predetermined position.

3. The combination, in a double-carbon lamp, of a releasing-stop for the feed mechanism of one of the carbon-carriers, mounted 70 on a lever, and a lug or projection on the other carbon-carrier, for tilting said lever and carrying said lever into releasing position when the latter carrier has moved to a predetermined point.

75 4. The combination, in a double-carbon lamp, of a feed clamp or clutch for one of the carbon-carriers, a releasing-stop for said clutch, mounted on a lever placed to hold the stop out of releasing position, and a projection on or connected with the other carbon-carrier, for tilting said lever and moving the stop into releasing position.

5. The combination, in a double-carbon lamp, of a releasing-stop for the feed-controlling 85 clamp of one carrier and means connected directly or indirectly with the other carrier for controlling the position of said stop, as and for the purpose described.

6. The combination, with two carbon-carriers, of a releasing-stop for the feed clamp or clutch of one carrier, means connected with the other carrier for setting said stop into releasing position, and a stop or catch for limiting the movement of the releasing-stop in the 90 setting operation.

7. The combination, with two carbon-carriers, of feed clamps or clutches actuated by a common magnet system, a fixed releasing-stop for the clamp or clutch of one carrier, 100 and a movable releasing-stop for the clamp or clutch of the other, set by a button or other suitable device connected with or controlled by the first carrier.

8. The combination, with a clutch for a carbon-carrier, of a releasing-stop, t , mounted on or supported by one arm of a lever, and a button-stud or its equivalent, as described, upon the other carrier, which button or stud engages with the other end of the lever when 105 the carbon is wholly or nearly consumed.

9. The combination of a carbon-carrier, R^2 , a feed-clutch, C^2 , a stop, t , a lever, T, a carbon-carrier, R, and button B.

10. In a double-carbon lamp, the combination, with the feed-controlling mechanism engaging with one carbon or carrier, of a releasing-stop, detent, or such like releasing device adapted to cause a release of said feed mechanism whenever, through wasting of said carbon in the arc, the feed-controlling mechanism is lowered to a predetermined extent, said releasing device being mounted in a movable support, of means for holding the same out of feed-releasing position while the other of the 115 two carbons is in action.

11. The combination, in a double-carbon lamp, of feed-regulating devices for the two carriers, and a fixed and a movable releasing-stop for the respective feed devices of said carriers, mounted on a common adjustable support, as and for the purpose described.

12. In a double-carbon electric lamp, the adjustable support P, carrying the fixed re-

leasing-stop J, for one carrier and the movable releasing-stop t for the other carrier, as and for the purpose described.

13. The combination, with the two carbon-carriers R R², of the clutches C C², releasing-stops J t , a movable support for stop t , and means connected with carrier R for setting the stop t in releasing position.

Signed at New Britain, in the county of Hartford and State of Connecticut, this 29th day of March, A. D. 1883.

ELIHU THOMSON.
